AIR TRAFFIC CONTROL TOWER

John H. Criswell, Berea, Anthony A. Coletto, Jr., Cleveland Heights, and Charles L. Benzon, Middleburg Heights, Ohio, assignors to Air Traffic Control Systems, Inc.

Filed Aug. 30, 1968, Ser. No. 13,342

Term of patent 14 years

Int. Cl. D25—04

U.S. Cl. D13—1

FIG. 1

FIG. 2

FIG. 3

FIG. 4

FIG. 1 is a perspective view of an air traffic control tower embodying our design;

FIG. 2 is a top plan view of the same;

FIG. 3 is a rear view of the same as seen from the end opposite to the end seen in FIG. 1; and

FIG. 4 is a side view of the same as seen from the side opposite to the side seen in FIG. 1.

The dotted line portions of the drawings are for illustrative purposes only.

We claim:

The ornamental design for an air traffic control tower, as shown and described.
